UNITED STATES PATENT OFFICE.

PETER J. SERIO, OF BIRMINGHAM, ALABAMA.

DIE FOR MACARONI AND THICK FLUID SUBSTANCES.

1,126,098.

Specification of Letters Patent. Patented Jan. 26, 1915.

Application filed March 31, 1911. Serial No. 618,259.

To all whom it may concern:

Be it known that I, PETER J. SERIO, a citizen of the United States, residing at Birmingham, in the county of Jefferson and State of Alabama, have invented new and useful Improvements in Dies for Macaroni and Thick Fluid Substances, of which the following is a specification.

My invention relates to an improvement in detachable circular macaroni molds and like molds for use in presses for thick fluid substances, and my object is to protect the mold, which is thick, heavy and formed of soft copper, from becoming injured by being constantly dropped upon the cross braces or spider support therefor at the bottom of the press cylinder.

According to the present practice in making macaroni, presses having relatively small cylinders have given the best results and the most uniform product. These presses have at their bottoms strong metallic cross bars or spider supports upon which the macaroni mold is detachably supported. These bars 25 may be arranged as a spider having a solid center and four radial arms which are attached at their ends to the bottom of the cylinder, or the bars may be arranged as cross bars and disposed in parallelism, there being two or more according to the size of the press cylinder. In each case the macaroni mold has spaces left free from perforations which correspond to the arrangement of cross bars. These molds are lowered by 30 hand into the press cylinder and the operator endeavors to adjust the mold so that as it falls its unperforated spaces will strike the cross bars or web thereby avoiding injury to the mold which would result if the 35 perforated portions of the soft heavy mold struck the cross bars. As a matter of fact, it rarely happens that the heavy mold will fall as desired and consequently after use for a comparatively short time, the row or rows 40 of macaroni holes bordering the unperforated spaces become mashed in and frequently entirely closed, thereby materially decreasing the available output from the mold and necessitating the mold being sent. 45 at considerable expense, to be repaired. All this is avoided by the provision of raised bearing surfaces along the under side of the unperforated portions of the mold and I prefer to form these surfaces of a hard 50 metal plate attachment instead of making them integral with the mold.

To this end I provide a reinforcing or bearing plate attachment for the bottom face of the mold, forming it preferably by stamping it out of thin sheet metal in a form which will cover the unperforated portions of the mold when attached thereto and provide a bearing surface sufficiently raised to protect the perforated portions of the mold from striking any part of the cross bars or spider or from being injured when the mold is out of the cylinder.

This being generally the object of my invention, I have illustrated the preferred embodiment thereof in the accompanying drawings forming a part of the specification, and in which:

Figure 1 is a side elevation of a macaroni press, the cylinder being broken away to show my improved mold in position therein. Fig. 2 is a bottom plan view of a macaroni mold with raised bearing surfaces formed by an attached plate. Fig. 3 is a plan view of the bearing plate detached. Figs. 4 and 5 are views of different styles of bearing plates. Fig. 6 is a cross sectional view of a mold having raised bearing surfaces integral therewith.

Similar reference numerals refer to similar parts throughout the drawings.

I have illustrated my invention in connection with a standard form of macaroni press having a cylinder 1 into which the plastic material is introduced in bulk for the purpose of being expressed into any of the various forms of macaroni according to the character of openings in the mold 2. This mold is supported upon a heavy metal cross brace or spider 3 having transverse webs 4 and end portions 5 and 6, which are respectively connected to and supported by uprights 7 and 8. The cross piece has a peripheral portion 9, which projects into and forms a shoulder at the bottom of the cylinder 1. The mold is formed of a thick heavy copper plate provided with suitably shaped openings 10 which may or may not have a central pin (not shown), according to the character of the macaroni to be made.

The mold is shown in bottom plan view in Fig. 2, where it is seen to be a circular plate having quadrant shaped groups of holes 10 which are separated by unperforated diametrical cross spaces 11 and the peripheral rim space 12 which conform to the size and arrangement of the webs 4 and the shoulder 9, respectively, which form the

supports for the mold. This arrangement is necessary to permit the plate when dropped into position in the cylinder, to be adjusted by hand until the spaces 11 come opposite to 5 and stand over the webs of the spider. This prevents the spider blocking or chocking any of the macaroni openings. It is very rarely the case that the plate, as it is dropped, will fall on the spider so that its 10 unperforated portions only will strike the spider. It follows therefore that the spider will strike and indent the plate, and I find in practice that these indentations usually occur anywhere within a space correspond- 15 ing to that between the lines *a—a* and *a—b* of Fig. 2, causing the bottom of the openings within such space and on each side of each unperforated portion to be more or less closed up. To avoid this injury to the mold 20 and materially increase its life, I provide a raised bearing plate attachment which I usually make from thin sheet metal of preferably about one-eighth of an inch in thickness, which plate is provided with a mar- 25 ginal rim portion 13 connected by cross sec- tions 14 arranged to underlie the unperforated portions 11 of the mold. The outer edge or rim of the attachment 13 conforms in shape to the outer edge of the mold, the 30 width of this rim being equal to or slightly less than the shoulder 9 and the unperforated peripheral space 12 of the mold. The plate has holes 15 to receive rivets, screws or other suitable means to fasten it to the un- 35 derside of the mold, its cross members 14 being arranged so that they underlie the unperforated portions 11 of the mold and project the thickness of the plate below the bottom surface of the mold so that as the 40 mold is dropped into place the plate strikes the spider and protects the mold from injury.

Another advantage in having the raised bearing surfaces lies in the fact that the 45 mold can be so readily adjusted with its unperforated portions in line with the spider, the operator being able to reach under the cylinder and readily grasp the cross sections 14 and move them into position above 50 the webs and thus adjust the mold without having to look to see that all the openings will clear the webs as is now necessary.

In view of the high cost of the metal from 55 which the macaroni molds are made and the difficulty of grinding off the wires at the bottom of the mold openings, I prefer to stamp the bearing plate attachments of harder and cheaper metal and attach them

to the molds rather than to form the mold as shown in Fig. 6 with raised bearing por- 60 tions 16 along the bottom faces of its unper- forated portions.

The bearing plates are designed to conform to any of the various types of macaroni molds, many of which have different 65 arrangements of their unperforated trans- verse portions to correspond to the different arrangements of the supports or spiders at the bottom of the press cylinder. In Fig. 4 I show a bearing plate having two parallel cross members 17 for use with a mold of that type. In Fig. 5 I show the plate with three cross members 18 for use with larger 70 sizes of molds that require three parallel cross webs to support same. 75

While I have defined my invention as peculiarly appropriated to the art of manu- 80 facturing macaroni, yet it is obvious that the manner in which I protect my heavy soft mold will be advantageous in other arts 85 where the mold is dropped into place upon cross supports and has apertures which are liable to be indented and closed by strik- ing said supports.

Having thus described my invention, what 85 I claim as new and desire to secure by Letters Patent, is:—

1. Circular macaroni mold formed of a thick soft metal plate having sections thereof 90 perforated and separated from each other and the margin of the plate by narrow unperforated sections, and hard metal raised bearing surfaces attached to and disposed along the underside of said unperforated sections. 95

2. A circular macaroni mold formed of a thick soft metal plate adapted to be sup- 100 ported on a spider and having narrow mar- ginal and transverse unperforated portions adapted to overlie and substantially con- form to the design of its spider support and having perforated portions between the unperforated portions, and a hard metal attachment for the underside of the mold comprising a plate, substantially shaped to 105 conform to and fit under said unperforated portions, which is raised relatively to the perforated surfaces of the mold.

In testimony whereof I have hereunto set my hand in presence of two subscribing 110 witnesses.

PETER J. SERIO.
